UNITED STATES PATENT OFFICE.

EUGÈNE SCHNEIDER, OF PARIS, FRANCE.

ECCECTRIC-REVERSING GEAR.

1,275,095.

Specification of Letters Patent.

Patented Aug. 6, 1918.

Application filed February 14, 1918. Serial No. 217,203.

To all whom it may concern:

Be it known that I, EUGÈNE SCHNEIDER, a citizen of the French Republic, and a resident of 42 Rue d'Anjou, Paris, France, have 5 invented new and useful Improvements in Eccentric-Reversing Gear, which invention is fully set forth in the following specification.

This invention has for its object to provide an improved eccentric reversing gear suitable for actuating slide valves, engines, pumps and for other purposes.

The invention consists in providing an improved means which will allow of reversing in a simple and rapid manner the angle of the eccentric actuating a slide valve or the like relatively to the shaft driven by the motor or the pump, and from which the eccentric rod receives its motion.

According to this invention the eccentric sheave, instead of being fixed on its driving shaft, is loose on said shaft, which latter is slidable longitudinally with relation to the eccentric sheave. The eccentric sheave carries 20 two engaging parts formed in or on its two respective ends, preferably at equidistant and diametrically opposite points. The said driving shaft has formed on or in it two engaging members adapted to coöperate 25 with one or the other of the engaging members formed on the eccentric sheave, the engagement between an engaging member of the shaft and an engaging member of the eccentric sheave being effected by suitably 30 sliding the driving shaft in the requisite direction and rotating the said shaft through the desired reversing angle. The angular 35 distance apart of the two engaging members on the driving shaft corresponds to the angle necessary for reversing the angular 40 position of the eccentric.

For the purpose of facilitating the driving of the eccentric sheaves in the direction of the motion of the driving shaft when two coöoperating engaging members are in engagement, without allowing too great a strain upon the said coöperating members, the eccentric sheave is provided with two oppositely directed stops projecting one 45 from each disk of the eccentric sheave. A tappet projecting from the support of each of the coöoperating engaging members carried by the driving shaft is adapted to bear 50 against the stop formed on the corresponding eccentric sheave disk. The said stops on the eccentric sheave disks may be located at

points diametrically opposite to the corresponding engaging members. The engagement between the said tappet and the corresponding stop is designed to take place 60 at the same instant as engagement takes place between the corresponding coöperating engaging members.

A practical embodiment of this invention is illustrated by way of example in the accompanying drawings in which:

Figure 1 is a longitudinal section partly in elevation of the improved gear taken along the axis of the slidable driving shaft.

Fig. 2 is a cross section on the line II—II 70 of Fig. 1.

Fig. 3 is a cross section on the line III—III of Fig. 1.

In the example shown, A indicates a slide-valve that is suitably guided in such a manner as to be capable of being actuated by the rod B of the eccentric strap C embracing an eccentric sheave E.

According to this invention the eccentric sheave E is loose on the driving shaft D 80 which is longitudinally slidable by any suitable means (not shown) in bearings d, d and d¹, in relation to the eccentric sheave E. The sheave E may be prevented from receiving any longitudinal motion by means 85 of one of the central bearings d¹. The sheave carries two engaging members such as the recesses e¹ and e² formed respectively in the disks E¹ and E² at points preferably equidistant from the centers of said 90 disks and located diametrically opposite each other. F¹ and F² are supports keyed by means of keys f¹, f² on the driving shaft D; they are located one on each side of the eccentric sheave E. These supports carry each 95 a projecting engaging member, such as a spring bolt G¹, G² respectively. The angular distance between the two bolts is equal to the angle through which it is necessary to reverse the eccentric in order to change from 100 forward running to backward running and vice versa.

At a point diametrically opposite the respective recess e¹, e², each of the disks E¹, E² of the eccentric sheave carries a stop h¹, h². 105 At a point diametrically opposite the respective bolt G¹, G², each of the supports F¹, F², keyed on the shaft D carries a tappet g¹, g² respectively.

In the figures the engaging members are 110 shown in the positions they occupy when the eccentric is fixed relatively to the driv-

ing shaft D, or more strictly speaking when the eccentric sheave E has been moved into the position for forward running. The axial distance between the supports F^1 and 5 F^2 is such as to allow of a suitable extent of sliding movement of the shaft D for the purpose of disengaging one of the bolts, for instance the bolt G^1 , and subsequently engaging the other bolt, for instance the bolt G^2 .
10 When this displacement is effected, the bolt G^1 is first disengaged so that the eccentric sheave is then free. Immediately afterward however, and as soon as the bolt G^2 is rotated with the shaft D, through the reversing angle α , the said bolt G^2 will engage in the recess e^2 , and the engagement of the tappet g^2 with the stop h^2 will assure the engagement between the said bolt and its recess at the proper moment, and will 15 relieve the said bolt and said recess from all shearing strain during their engagement.

What I claim is:—

1. In eccentric reversing gear, the combination of a rotating driving shaft longitudinally slidable in both directions in its bearings, a rotatable eccentric loose on said shaft, two disks fixed one to each end of said eccentric, two engaging members carried one by each of said disks, two supports fixed on said shaft, one outside each of said disks, and two engaging members carried one by each of said supports and spaced apart at the desired reversing angle, whereby on sliding said shaft in the required direction so as to engage one or the other of said engaging members with the engaging member of the corresponding eccentric disk, the said eccentric sheave is reversed as desired.
20 2. In eccentric reversing gear, the combination of a rotating driving shaft longitudinally slidable in both directions in its bearings, a rotatable eccentric loose on said

shaft, two disks fixed one to each end of said eccentric, two recesses formed one in each of said disks, two supports fixed on said shaft, one outside each of said disks, and two projecting members carried one by each of said supports, and spaced apart at the desired reversing angle, whereby on sliding said shaft in the required direction so as to engage one or the other of said projecting members into the corresponding recess of the corresponding eccentric disk, the said eccentric sheave is reversed as desired. 55

3. In eccentric reversing gear, the combination of a rotating driving shaft longitudinally slidable in both directions in its bearings, a rotatable eccentric loose on said shaft, two disks fixed one to each end of said eccentric, two engaging members carried one by each of said disks, two supports fixed on said shaft, one outside each of said disks, two engaging members carried one by each of said supports, and spaced apart at the desired reversing angle, two projections carried by each of said disks, and two driving projections cooperating therewith carried by each of said supports, spaced apart at the reversing angle, whereby on sliding said shaft in the required direction so as to engage one or the other of said engaging members with the engaging member of the corresponding eccentric disk, the said eccentric sheave is reversed as desired, and 70 also whereby the co-operation between each of said projections and the corresponding one of said driving projections will relieve said engaging members of all shearing strain. 75

In testimony whereof I have signed this specification.

EUGÈNE SCHNEIDER.
